UNITED STATES PATENT OFFICE.

CARL S. FOGH, OF PHILADELPHIA, PENNSYLVANIA.

METHOD OF PRODUCING ELEMENTAL SULPHUR.

Application filed October 23, 1920. Serial No. 419,021.

To all whom it may concern:

Be it known that I, CARL S. FOGH, a subject of the King of Denmark, residing at Philadelphia, in the county of Philadelphia 5 and State of Pennsylvania, have invented certain new and useful Improvements in Methods of Producing Elemental Sulphur, of which the following is a specification.

My invention relates to the recovery of 10 elemental sulphur from sulphide ores or other sulphur-bearing material from which the sulphur may be volatilized by heat alone.

It has for its object not only to recover 15 sulphur but to assist in the elimination of the sulfurous fume nuisance by avoiding, to a material extent, the production of such fumes.

Many sulfide ores have a pyrite (FeS_2) content, from which one atom of sulphur can 20 be volatilized by heat alone. There are also found certain deposits where elemental sulphur is physically combined with a siliceous gangue. My process is applicable to either of such products.

25 The process comprises continuously feeding the material from which the sulphur is to be eliminated into and through a practically gas-tight mechanically rabbled roasting furnace preferably of the multiple hearth type, such as the well-known Wedge furnace. As the material passes over the hearths of the furnace, it is subjected to hot gases containing practically no free oxygen, and in such volume and at such temperature that 30 the sulphur will be volatilized. The gases evolved from the furnace are passed through a suitable dust-separator and the cleaned gas is then passed through a suitably cooled chamber or condenser in which the sulphur 35 is condensed and collected either as brimstone or flowers of sulphur. The residual gases from the condenser are then passed through a heater within which they are heated to the requisite temperature and again 40 introduced into the furnace. Suitable flues and fans are provided for maintaining the continuous circulation of the gases through the system.

45 A diagrammatic representation of a plant for carrying out the process is shown in the accompanying drawing in which 1 is a multiple hearth roasting furnace provided with a hopper 2 for introducing the ore, a delivery chute 3, and mechanism 4, for operating the 50 stirrer arms. The gases pass from the fur-

nace through flue 5 to a dust arrester, 6, from which the gases pass by flue 7 to the condenser, 8, wherein the sulphur is condensed and removed through discharge chute 9.

From the condenser, the residual gases 60 pass through flue 10, fan 11 and flue 12 to a heater or heat interchanger, here shown as a chamber 13 encircling the pipe 14, which may be heated by any suitable means such as an oil, gas, or coal burner. From the 65 chamber 13, the hot gases pass into flue 15 and thence by one or more pipes 16 into one or more of the hearths of the furnace 1.

In starting the operation of such a plant, the furnace is heated and started in the same 70 manner as is now done in smelter practice, and of course SO_2 and SO_3 gases will be formed, which are circulated through the system until the oxygen in the system has been practically exhausted, when the temperature of the gases is raised by the heater 75 to a point which will volatilize the sulphur from the ore or sulphur-bearing material being fed through the furnace. This sulphur vapor is carried by the circulating gases to 80 the condensing chamber in which it is precipitated, and the non-oxygen-bearing gases are again circulated through the heater and furnace.

The process is therefore continuous. The 85 raw material is continuously fed to the furnace. The residual material is continually discharged therefrom, and the sulphur vapor is produced by the continuous circulation of the heating gases. This method avoids the 90 difficulties incident to operating muffle fired furnaces, and obviates the objections to batch processes or operation of retorts. It has the further advantage that it provides for the treatment of large tonnages of material, an 95 essential requisite in most smelting plants.

What I claim is:

1. The continuous process of volatilizing sulphur from sulphur-containing materials which consists in heating such material, during its passage through a gas-tight mechanically rabbled furnace, by contact with non-oxidizing gases heated to temperature sufficient to volatilize sulphur removing the gases carrying sulphur vapor from the furnace in 105 continuous flow, separating out any dust particles therefrom, condensing the sulphur from said gases, reheating the residual gases to a sufficient temperature to cause volatilization of sulphur from the material passing 110

through the furnace, and passing such heated gases into the furnace.

2. The continuous process of volatilizing sulphur from sulphur-containing materials which consists in heating such material, during its passage through a gas-tight mechanically rabbled furnace, by contact with non-oxidizing gases heated to temperature sufficient to volatilize sulphur removing the gases carrying sulphur vapor from the furnace in continuous flow, condensing the sulphur from said gases, reheating the residual gases to a sufficient temperature to cause volatilization of sulphur from the material passing through the furnace, and passing such heated gases into the furnace.

3. The continuous process of volatilizing sulphur from pyrite containing ores which consists in heating such material, during its passage through a gas-tight mechanically rabbled furnace, by contact with non-oxidizing gases heated to temperature sufficient to volatilize one atom of sulphur, removing the gases carrying sulphur vapor from the furnace in continuous flow, condensing the sulphur from said gases, reheating the residual gases to a sufficient temperature to cause volatilization of sulphur from the material passing through the furnace, and passing such heated gases into the furnace. 20 25 30

In testimony whereof, I affix my signature.
CARL S. FOGH.
